UNITED STATES PATENT OFFICE

96,865

DESIGN FOR A COMBINATION COOK STOVE AND UTILITY CABINET

George Steingruber, Huntsville, Ala.

Application June 24, 1935, Serial No. 57,391

Term of patent 7 years

To all whom it may concern:

Be it known that I, George Steingruber, a citizen of the United States, residing at Huntsville, in the county of Madison and State of Alabama, have invented a new, original, and ornamental Design for a Combination Cook Stove and Utility Cabinet, of which the following is a specification, reference being had to the accompanying drawing, forming part thereof.

The figure of the drawing is a perspective view of my new design.

The hidden side of the article is substantially the same as the side shown except that the switch is omitted.

I claim:

The ornamental design for a combination cook stove and utility cabinet, substantially as shown and described.

GEORGE STEINGRUBER.
